DESIGN FOR A COMBINED TOILET PAPER HOLDER AND ASH TRAY

Anthony B. Fortener, Miamisburg, Ohio

Application December 30, 1940, Serial No. 97,726

Term of patent 7 years

To all whom it may concern:

Be it known that I, Anthony B. Fortener, a citizen of the United States, residing at Miamisburg, in the county of Montgomery and State of Ohio, have invented a new, original, and ornamental Design for a Combined Toilet Paper Holder and Ash Tray, of which the following is a specification, reference being had to the accompanying drawing, forming part thereof.

The single figure of the drawing is a perspective view of a combined toilet paper holder and ash tray, showing my new design.

I claim:

The ornamental design for a combined toilet paper holder and ash tray, as shown.

ANTHONY B. FORTENER.
